CYCLE TIMER

Filed Oct. 30, 1968

Fig. 3.

FREDRIC S. MILLER INVENTOR.

BY
Seyman Jackman
ATTORNEY

engaging the switch actuator as the assembly rotates. Also, this view shows the actuator portion of the strip varying in circumferential extent. Thus, it will be clear that the full cycle, represented by the total circumference of the disc, may be divided into a great variety of switch-actuating portions, of varying extent and circumferential spacing.

The pins may be numbered or otherwise coded so the subcycle arrangement can easily be effected.

In the form of the invention shown in FIG. 3, the pins 23a are shown as extending radially from the peripheral edge 20a of the disc 7a, and the strip 25a as interwoven with said pins so the outwardly trained, actuator-engaging portions of said strip have an approximately coplanar relation to the plate 19a of the disc. This arrangement 15 will require that the control component 6 be placed above or below the disc, thereby providing a more compact arrangement than the arrangement of FIG. 1.

While the foregoing has illustrated and described what are now contemplated to be the best modes of carrying 20 out the invention, the constructions are, of course, subject to modification without departing from the spirit and scope of the invention.

Having thus described the invention, what is claimed and desired to be secured by Letters Patent is:

1. A cycle timer comprising:

- (a) a rotatable member mounted on an axis of rotation,
- (b) a complement of circumferentially spaced pins on said member circumferentially arranged around said axis as a center, and
- (c) a flexible strip adapted to be variously interwoven among the pins to present portions thereof on one side of the pins and of varying circumferential extent according to the manner of interweave of the strip, the remaining portions of the strip being disposed on the opposite side of the said pins,
- (d) said first-mentioned portions of the strip being adapted to engage the actuator of a control component and, during movement of the rotatable member, alternately engaging and moving and then releasing said actuator of the control component for periods of various duration according to the manner and variety of circumferential extent of said first-mentioned portions of the strip.

2. A cycle timer according to claim 1 in which the

pins are disposed adjacent to the peripheral edge of the rotatable member and parallel to said axis.

3. A cycle timer as defined in claim 1 and in which the rotatable member is provided with an annular shoulder, the complement of pins being radially spaced from said shoulder.

4. A cycle timer according to claim 1 in which the pins are radially directed from a peripheral edge of the rotatable member.

5. A cycle timer as defined in claim 1, further comprising a uniformly operating drive unit having a driven shaft, the rotatable member being mounted on said shaft and uniformly rotated thereby.

6. A cycle timer comprising:

- (a) a movable member provided with a plurality of spaced projections, and
- (b) a strip of flexible material having portions thereof introduced variously in the spaces among the projections to present said strip portions on one side of the projections of varying linear extent according to the manner of introduction of the strip portions,
- (c) said portions of the strip being adapted to engage the actuator of a control component and, during movement of the mentioned member, alternately engaging and releasing said actuator for periods of varying duration according to the linear extent of said strip portions.
